Primary Examiner—Dominic Simone

[57] **CLAIM**

The ornamental design for a flat sided toy rocket, as shown.

DESCRIPTION

FIG. 1 is a top, front, right side perspective view of a flat sided toy rocket showing my new design;

FIG. 2 is a front elevation view thereof;

FIG. 3 is an enlarged cross-sectional view taken along line III—III of FIG. 2;

FIG. 4 is an enlarged cross-sectional view taken along line IV—IV of FIG. 2;

FIG. 5 is an enlarged cross-sectional view taken along line V—V of FIG. 2;

FIG. 6 is a left side elevational view thereof, the right side elevational view being the mirror image thereof;

FIG. 7 is a rear elevational view thereof;

FIG. 8 is an enlarged top plan view thereof; and,

FIG. 9 is an enlarged bottom plan view.
